UNITED STATES PATENT OFFICE.

SAMUEL R. FRAIM, OF LANCASTER, PENNSYLVANIA.

PADLOCK.

Application filed June 17, 1924. Serial No. 720,656.

To all whom it may concern:

Be it known that I, SAMUEL R. FRAIM, a citizen of the United States, residing at Lancaster, in the county of Lancaster and 5 State of Pennsylvania, have invented certain new and useful Improvements in Padlocks, of which the following is a specification.

This invention relates to padlocks in general and more particularly to such a padlock adaptable for use in locker systems where a small padlock is required and made up in a large number of key changes, all operable by a master key.

15 An object of this invention is to provide a padlock of this character referred to, which will be simple and efficient in its operation, readily disassembled and assembled.

Another object of this invention is to 20 provide a locking mechanism to include a master lever and a plurality of change levers, the latter being interchangeable or adapted to have substitutions made therefor either in part or entirely to be operable independently of the master lever, by various 25 keys, the master lever being at all times operable by a master key independently of the change levers.

With the foregoing and other objects in 30 view, the invention consists in the combination and arrangement of parts and in the details of construction hereinafter described and more particularly set forth in the appended claims, certain embodiments of my 35 invention being illustrated in the accompanying drawings, in which:

Figure 1 is a front elevation of the padlock with the upper half of the casing removed, showing the shackle in locked position;

40 Figure 2 is a similar view showing the shackle in unlocked position;

Figure 3 is a similar view of the casing showing the locking bolt and master lever in 45 position with the remainder of the mechanism removed;

Figure 4 is a similar view showing the locking bolt and bolt lever in position;

Figure 5 is a view in perspective of the 50 locking bolt;

Figure 6 is a detailed view of master lever;

55 Figure 7 is a detailed view of all the change levers disassembled, showing the different locations of their single notches;

Figure 8 is a detailed view of the master key;

Figure 9 is a similar view of the ordinary key adapted to fit the particular lock illustrated in assembled position in Figures 60 1 and 2.

Referring more particularly to the drawings, the padlock consists of a casing, the lower half of which is shown in the drawings at 6, and is provided with studs 7, 8, 65 9 and 10.

The locking mechanism consists mainly in a locking bolt 11 with its actuating levers which will be described later. Referring to Figure 5 the locking bolt 11 being pivotally 70 mounted on the casing stud 10 has a recess 12 in its lower side, in which recess a plunger 13 extends through the hole 14 in the bolt. The bolt also has a notch 15 adapted to engage the notch 16 in the toe of the 75 shackle 17, while a lug 18 is arranged on the opposite side of the bolt.

A bolt lever 19 with an elliptical inclined slot 20 is mounted on the stud 9 so that the lever may slide on the stud. The 80 lever 19 is provided at its other end with a hole to receive the plunger 13 of the bolt 11 while the lever is fitted in the recess 12 in such a manner that a sliding movement of the lever rotates the bolt about its pivot 85 stud 10. An eccentric projection 19' forms a bearing surface whereby a key may effect the movement referred to above.

Placed upon the bolt lever 19 is a master 90 lever 22 pivotally mounted on the casing stud 8 by means of the hole 26, an elliptical slot 23 being arranged in the master lever to receive the casing stud 9 which limits a pivotal movement of the lever 22. The master lever is also provided with an upturned flange 24, the purpose of which will appear later in the description.

Five change levers 1, 2, 3, 4 and 5 are provided, having elliptical slots 31, 36, 41, 46 and 51; holes 32, 37, 42, 47 and 52; notches 34, 39, 44, 49 and 54; projections 35, 40, 45, 50 and 55; and leaf springs 33, 38, 43, 48 and 53 respectively. The notches and projections in each change lever have a different location so that the wards 65, 66, 67, 68 and 69 of the key 60 will actuate their corresponding change lever in such a manner as to bring the notches 34, 39, 44, 49 and 54 flush and be engaged simultaneously by the bolt lug 18. In this specific showing the 100 105 110

levers 1 to 5, inclusive, are placed upon the master lever in the order mentioned being 5 their common pivot 8. A plate 58 is superimposed upon the lever 5 and is mounted stationary but removable on the studs 8, 9 and 10.

10 A spring 56 is coiled about the stud 10 and has at one end a downward extension 56' to bear against the heel of the bolt 11 while the other end of the spring bears against the casing tending to force the bolt 15 11 to the right about its pivot stud 10.

The shackle 17 having its heel and toe extending through the channels 29 and 30 of the casing with its heel pivoted on the stud 7, is provided with a spring 57 coiled 20 about the stud 7 and connected to the heel of the shackle, the spring 57 bearing on the stud 9 for normally forcing the toe upwardly about the shackle heel as a pivot.

A key bearing 70 having a slot 71 for 25 receiving either the key 59 or 60 is mounted in the perforation 30 in the casing. It will be understood from the foregoing description that when either key is used, a certain ward on the lower part of the bit engages 30 the bearing surface 19' of the bolt lever 19 as the key is rotated on its axis in the key bearing 70. As the bolt lever 19 moves to the right it is guided by means of its elliptical slot 20 sliding on the stud 9, and forced 35 by the key, the bolt 11, by means of its plunger 13 fitting in the hole 12 of the bolt lever, is drawn back out of engagement with the notch 16 of the shackle toe. The bolt is retained in its unlocked position by the 40 spring 56, the top of the bolt being milled off at its heel or stud end. The change levers 1, 2, 3, 4 and 5 being arranged in the order named on top of the master lever 22 are alike with the exception of the location of 45 the respective change notches 34, 39, 44, 49 and 54 and their extensions 35, 40, 45, 50 and 55, respectively, which are adapted to be engaged by the flange 24 of the master lever 22. The extensions are so arranged 50 that the ward 62 on the bit of the master key 59 raises the master lever 22.

The flange 24 of the master lever then 55 engages the projections 35, 40, 45, 50 and 55 of the change levers 1, 2, 3, 4 and 5, and raises the change levers so that all of the notches 34, 39, 44, 49 and 54 will register with the dog or lug 18 of the locking bolt 11. The movement of the bolt caused by the 60 spring 56 in engaging these notches constitutes sufficient movement to cause the notch 15 of the bolt to disengage the corresponding notch 16 of the toe of the shackle, releasing the shackle toe which is forced out of the casing by the action of the spring 57.

65 The plate 58 is placed over the uppermost

change lever 5 simply as a filler plate. However, it may readily be used in connection with other master key change combinations by locating it in different positions interposed between any selected two of the 70 change levers. In this case the key bearing surface on the plate would extend to a certain radius whereby the ward on the key biting would just pass through.

In the regular operation of the padlock 75 using the standard change key, the ward, on the key, which could register with the master lever is cut down sufficiently to either pass by it entirely without touching it or moving it slightly (not enough to allow the 80 flange 24 of the master lever 22 to engage any of the change lever extensions). The change levers are accordingly raised by the action of their respective wards on the key 85 bitting as already described. In this connection it will be observed that I have illustrated the master lever 22 as not being provided with a notch to register with the notches in the change levers. The front 90 faces of the change levers extend beyond that of the master lever so as not to interfere with the engagement of the bolt lug 18 with the change lever notches.

The master key 59 is cut away at 63, allowing the ward 62 to engage the master 95 lever and the bolt lever, the cut away portion 63 being for the purpose of preventing the master key from engaging any of the change levers. Thus the ward 62 by means 100 of a rotation of the master key to the right simultaneously actuates the bolt lever 19 to retract the locking bolt 11 from engagement with the shackle toe, and engages and raises the flange 24, forcing the master lever together with the change levers so that the 105 bolt lug 18 engages the change lever notches to effect an unlocking as described.

This simplicity and efficiency of this construction is apparent, in that the regular 110 key operates the change levers alone, the master lever not being used at all; while the master key operates the lock through the medium of the master lever alone and does not engage the change levers directly, 115 the master lever being relied on to raise the same.

It will be understood that while I have described and illustrated certain combinations and arrangements of parts, I do not 120 wish to limit my invention to such specific disclosures, but only in so far as to fall within the scope of the appended claims.

I claim—

1. A padlock comprising, in combination, 125 a casing, a shackle pivotally mounted therein, a sliding bolt lever, a locking bolt also pivotally mounted in said casing and adapted to be actuated by said bolt lever to engage and disengage said shackle, a master lever, and a plurality of change levers 130

5 mounted on a common axis and adapted to regulate the movement of said locking bolt, said change levers being operable independently of said master lever, the latter being operable alone to actuate all of said change levers.

10 2. A padlock, comprising a casing and a shackle pivotally mounted therein, a locking bolt for engaging said shackle, a sliding bolt lever, and for moving said bolt into and out of locking position, a master lever, a plurality of change levers mounted on a common axis, said change levers being spring pressed to normally prevent retraction 15 of said locking bolt, said change levers being provided with selectively located notches to register with a corresponding dog on said bolt to allow the retraction of the latter, said change levers being operable independently 20 of said master lever, and said master lever being operable alone to actuate all of said change levers.

25 3. A padlock, comprising a casing and a shackle pivotally mounted therein, a locking bolt pivotally mounted in said casing and adapted to engage said shackle, a sliding bolt lever for moving said bolt into and out of locking position, a master lever, provided with an upstanding flange, a plurality 30 of change levers spring-pressed to normally prevent retraction of said locking bolt, said master and change levers being mounted on a common axis, said change levers being provided with selectively located notches to register with a corresponding 35 dog on said bolt to allow the retraction of the latter, all of said change levers being projections directly beneath their notches, said change lever being operable independently 40 of said master lever, and said master lever being operable alone to actuate all of said change levers by means of the flange of the latter engaging the projections of the former.

45 4. A padlock comprising, in combination, a casing a shackle pivotally mounted therein, a sliding bolt lever, a locking bolt also pivotally mounted in said casing and adapted to be actuated by said bolt lever to engage and disengage said shackle, a master lever, and a plurality of change levers mounted on a common axis and adapted to regulate the movement of said locking bolt, said change 50 levers being operable independently of said master lever, the latter being operable alone to actuate all of said change levers, said bolt lever having an inclined slot whereby it is slidably mounted on a stud of said casing, said bolt lever being connected to said bolt and having a bearing surface adapted to be engaged by suitable change and master keys for retracting said bolt from said shackle when the change levers are in the proper position to allow such movement of the bolt.

5. A padlock, comprising a casing and a shackle pivotally mounted therein, a locking bolt for engaging said shackle, a sliding bolt lever for moving said bolt into and out of locking position, a master lever and a plurality of change levers mounted on a common axis, said change levers being spring pressed to normally prevent retraction of said locking bolt, said change levers being provided with selectively located notches to 70 register with a corresponding dog on said bolt to allow the retraction of the latter, said change levers being operable independently of said master lever, and said master lever being operable alone to actuate all of said 80 change levers, said bolt lever having an inclined slot whereby it is slidably mounted on a stud of said casing, said bolt lever being connected to said bolt and having a bearing surface adapted to be engaged by suitable change and master keys for retracting said bolt from said shackle when the change levers are in the proper position to allow such movement of the bolt.

6. A padlock, comprising a casing and a shackle pivotally mounted therein, a locking bolt pivotally mounted in said casing and adapted to engage said shackle, a sliding bolt lever for moving said bolt into and out of locking position, a master lever provided with an upstanding flange, a plurality of change levers spring-pressed to normally prevent retraction of said locking bolt, said master and change levers being mounted on a common axis, said change levers being provided with selectively located notches to register with a corresponding dog on said bolt to allow the retraction of the latter, all of said change levers being projections directly beneath their notches, said change 100 lever being operable independently of said master lever, and said master lever being operable alone to actuate all of said change levers by means of the flange of the latter engaging the projections of the former, said bolt lever having an inclined slot whereby it is slidably mounted on a stud of said casing, said bolt lever being connected to said bolt and having a bearing surface adapted to be engaged by suitable change and master keys for retracting said bolt from said shackle when the change levers are in the proper position to allow such movement of the bolt.

7. A padlock comprising, in combination, a casing a shackle pivotally mounted therein, a sliding bolt lever, a locking bolt also pivotally mounted in said casing and adapted to be actuated by said bolt lever to engage and disengage said shackle, a master lever, and a plurality of change levers mounted on a common axis and adapted to regulate the movement of said locking bolt, said change levers being operable independently of said master lever, the latter be-

ing operable alone to actuate all of said change levers, said bolt lever having an incline slot whereby it is slidably mounted on a stud of said casing, said bolt lever being connected to said bolt and having a bearing surface adapted to be engaged by suitable change and master keys for retracting said bolt from said shackle when the change

levers are in the proper position to allow such movement of the bolt, said bolt having 10 a recess therein to receive the corresponding arm of said bolt lever, a pin located in the bolt in its recess adapted to engage a perforation in the bolt lever.

In testimony whereof I affix my signature.

SAMUEL R. FRAIM.
